METHOD AND MEANS OF MAKING X-RAY PHOTOGRAPHS

Clyde R. Landis and William L. Culpepper, Chicago, Ill., assignors to Don B. McCloud, Du Quoin, Ill.

Continuation of application Serial No. 403,269, July 21, 1941. This application August 27, 1943, Serial No. 500,260

15 Claims. (Cl. 250—65)

This application is a continuation of my allowed application for patent, Serial No. 403,269, filed July 21, 1941, and this invention relates to a new method and means of marking X-ray photographs commonly known as roentgenograms, a novel intensifying screen or marking means and a method and means of making the same whereby such roentgenograms or radiographs can be easily marked in taking an X-ray picture so as to clearly and accurately indicate at a glance, especially by a trained X-ray specialist or doctor, alignment or degree of misalignment of the bony structures of the human body and their spaced relationship to each other so that in the latter case, proper effectual treatment may be prescribed or given for correction. Looking at the bony structure of the human body from a so-to-speak mechanical standpoint, we find that it consists of numerous parts or bones held together by divers types of joints or other connecting media and the entire body is supported by this structure. In taking a photograph and marking the same in accordance with the present invention, this is done by producing on the film easily discernible vertical and horizontal markings or lines equally distant apart in the manner of cross-section paper, such markings or lines, however, being of such nature that they do not obliterate the details of the objects that appear in the picture. Certain parts of this bony structure are normally symmetrical. If a misplacement occurs, it sometimes cannot be discerned unless it is carefully compared with the placement of a similar member on the opposite side of the body because there are wide variations of the exact placement of parts in different individuals. For example, in the pelvis, the ilium, dorsal or upper part of each hip bone is attached to the sacrum which is surmounted by the spinal column. From a mechanical standpoint, when a normal person is standing erect with the weight distributed equally on each foot, a vertical plane passing from front to rear through the spinal column should bisect at right angles a horizontal line drawn from one sacro-iliac connection to the other. If a sacro-iliac displacement occurs on one side, it often cannot be discerned on the ordinary roentgenogram or X-ray photograph, film or picture of the pelvis but with a roentgenogram marked with horizontal and vertical cross-section lines as produced by this invention any change from a uniform bilateral structure of the bony members of the pelvis can be seen almost at a glance and there is no necessity for further measurement.

In the past, efforts have been made to construct devices for marking roentgenograms or producing cross-section markings on a radiograph by interposing an impermeable lead or light wire screen, such as an aluminum plate or grid with alternate layers or lines of aluminum and lead, between the

source of X-rays and thus the object or body being X-rayed or photographed and the sensitized film, such screens being made of material impervious to X-rays such as lead lines or wires placed 5 between the sensitized film and the source of X-ray emanations or placed adjacent to or some distance from the sensitized surface of the film which resulted not only in indistinct lines but in breaks, hiatuses or interruptions in the continuity 10 of the image. Results with such devices are unsatisfactory because the lines produced are blurred and the image of the object that is shown in the radiograph is not discernible or clearly discernible at line intersections because the continuity of the image is entirely broken by the lines since no 15 photograph or development of the image appears at such points. The method employed by this invention does not require anything of such nature to be interposed between the source of X-rays 20 and the sensitized film upon which the image is made and produces clear markings or lines and complete images of the bones or objects X-rayed or photographed and outlines thereof, including portions across, intersecting or crossing the markings, 25 so as not to break the continuity of the image or result in breaks which may be mistaken for from a fracture or break in the bone itself or interfere with the proper reading of the X-ray. In other words, the lines produced, while 30 easily discernible, do not obliterate or cause breaks in the continuity or the details of the image of any object, yet the lines are sharply defined due to the marker being in direct intimate contact with the sensitized surface of the 35 film during exposure.

In the past, the practice in taking radiographs consisted of exposing the sensitized surface of a film or plate to the direct emanations of X-rays. The sensitized surface of a film or plate consists 40 of a layer of emulsion containing certain silver compounds which are affected by X-rays or light rays. Formerly, this emulsion was applied to only one surface of a film. In modern practice, however, since both surfaces of a film are coated 45 with the sensitized emulsion, the present day radiograph may be said to consist of two facsimile pictures exactly superimposed one on the other and separated by the cellulose portion of the film itself. Most modern roentgenograms are 50 made on "dupletized" superspeed film using fast double screens. Instead of having only one side of the film coated with sensitized emulsion as was the case with previously used film and glass photographic plates, the new type film has sensitized 55 emulsion on both sides and is what is known as a double-coated duplex or "dupletized" film. Present day X-ray film is a result of a series of complex stages of development and basically the film itself does not constitute a part of this 60 invention, except the product as marked in ac-

cordance with the invention. "Dupletized" film thus brought about a new, modern technique in making radiographs or roentgenograms. Under present practices, the "dupletized" film is placed in a container known as a cassette. This cassette has a fixed front usually made of aluminum, Bakelite or some other material pervious to X-rays. There is a hinged or removable back by means of which the film is introduced into the cassette. The front of the cassette and the removable or movable back are each lined with an intensifying screen having a coating of calcium tungstate or the like, which renders the screen fluorescent or luminescent, especially when impacted by or exposed to X-rays. That is, the intensifier screen generates light by the impact of the X-rays upon it, thereby reflecting light rays toward the film. The "dupletized" film is firmly clamped in position between these two screens with which the film is in intimate contact and the sensitized surfaces of the film receive their photographic image in two ways, first by the piercing X-rays which causes a minor degree of the development, say approximately 20 to 25 per cent, and secondly by the light generated by the impact of the X-rays on the screens which causes the major degree of development of the film and image or sensitive emulsion coating thereon, say approximately 80 or 75 per cent. The light generated by the screens persists after the X-rays have been discontinued and mutual identical impressions or images are obtained on both sides of the film which, of course, constitute one combined image when the film is viewed. By means of this invention, it is possible to produce marking lines on only one surface of the film, leaving the opposite surface of the film unmarked. This makes the lines discernible without obliterating the image photographed. Thus, with a film having both surfaces covered with sensitized emulsion or what is known as a "dupletized" film, a radiograph made on such a film is ordinarily produced by the use of the intensifying screens involving the technique of placing such a film in the holder or cassette lined at the front and back by said screens results in the latter generating light corresponding to ordinary light rays as distinguished from X-rays, by the impact or projection of the X-rays upon the calcium tungstate or other material of the coating of the screens upon its fiber or cellulose body and the photographic image is, therefore, obtained by the two stimuli, one being the direct X-rays and the other being the light generated in opposite directions by the intensifying screens. The intensifying screen on the front of the cassette affects principally the emulsion on the surface of the film with which it is in contact, whereas the light from the intensifying screen on the back of the cassette affects principally the emulsion on the opposite side of the film while the X-rays affect both and develop both, even on the back, as the cross-section markings are not opaque or impermeable to the X-rays. In order to produce discernible lines on one of the sensitized surfaces of the film, the present invention provides a marker to be placed between the sensitized film and one of the intensifying screens used in the cassette. This marker consists of markings or lines drawn with india ink or any other opaque marking material, pigment, pencil or liquid on one of the intensifying screens so that the light rays from the latter being blocked off by the markings, will be produced on the film and being permeable by X-rays but

impermeable to ordinary light rays from the screen which produces the major degree of development of the image on the film as compared to the minor degree developed by the X-rays, the markings or lines will appear on the film as transparencies when the marker is interposed between one of the screens on which it appears and the sensitized film and both screens and the film are exposed to the X-ray emanations exactly as they would be if the marker was not used because the markings do not constitute a barrier or screen for the X-rays or prevent permeability of the radiations therefrom because they are easily penetrable by such rays and an image is produced by the rays on both sides of the film. After the X-rays have been discontinued, however, and each of the sensitized surfaces of the film is being affected by the secondary light produced by the adjacent intensifying screen, the image is completely developed on both sides of the film except on one side where the markings overlie or intersect the image and the lines on the marker opaque to or through ordinary light will cause easily discernible markings or lines to appear on the sensitized surface of the film to which it is adjacent but will prevent further development of the image on that surface or side although they will be visually distinguishable from the image, since the markings are substantially transparent and the image at points of intersections therewith will appear lighter, paler or not so dark as the image at other portions. The amount of deflection or misalignment can also be readily observed and measured so that proper treatment can be prescribed for correction with much greater facility than heretofore. This is, also, due to the fact that the markings are easily discernible and clear, yet not heavy enough to obliterate entirely or partially the image or outlines of the bony structures and, also, because the markings are impressed on one side only of the film as transparencies and not on the other but clearly visible entirely through the film from either side and hence the effect of looking at the image through the film is of an object superimposed on fine cross-section lines or markings which, however, do not destroy the details of the image or objects shown appearing on one or both sides of the film.

In our copending application, Serial No. 403,268, we have broadly covered a method and means of making X-ray photographs and marking the same, but the present invention is distinguishable therefrom in that the marking medium instead of being separate from an intensifying screen, is applied to or embedded in the luminous surface of the screen so as to produce clearer markings or lines.

Further objects and advantages will appear and be brought out more fully in the following specification, reference being had to the accompanying drawings, in which:

Fig. 1 is a diagrammatic side view with the cassette in end elevation and showing the method of producing an X-ray photograph and marking the same;

Fig. 2 is a rear elevation of the cassette;

Fig. 3 is an elevation of the cassette opened and showing the intensifying screens in position before the marking sheet and film are placed in position;

Fig. 4 is a section taken on the line 4-4 of Fig. 3;

Fig. 5 is an enlarged vertical section taken on the line 5-5 of Fig. 2;

Fig. 6 is a fragmentary sectional view at right angles to Fig. 5, taken on the line 6—6 of Fig. 2;

Fig. 7 is an elevation of the film;

Fig. 8 is a section of the film taken on the line 8—8 of Fig. 7;

Fig. 9 is an enlarged fragmentary cross-section taken on the line 9—9 of Fig. 3;

Fig. 10 is an enlarged face view of the developed film or negative photograph and looking toward the side having the markings thereon;

Fig. 11 is a view of a fragmentary portion of the developed film or picture, greatly enlarged;

Fig. 12 is a face view of a modified form of marking screen;

Fig. 13 is a fragmentary elevation of a film marked by the sheet shown in Fig. 12; and

Fig. 14 is an enlarged fragmentary cross-section of a modified form of marking screen corresponding to the screen in Fig. 9.

Referring more particularly to the drawings to illustrate the construction and operation of the invention, 15 designates an X-ray, roentgen or Crookes lamp or tube, or other source of X-rays which is suitably supported for adjustment in the usual way not necessary to be described herein and adapted for taking pictures of bodies arranged vertically or upright, or horizontally or in a reclining position. As indicated, 16 represents the mid-section of a body with a person standing in an erect position but it is to be understood that any other part of the body or any other object may be employed with equal facility. The X-rays are generally designated at 17, the body being interposed between the lamp and the frame or cassette 18 in which the film is held during the taking of the picture. The cassette may be supported upon suitable means such as represented at 19 with the cassette arranged vertically or horizontally and illustrated in the form shown as being arranged vertically with a suitable upright at the back. This cassette consists of a rectangular frame 20 of some metal such as aluminum or even Bakelite which the X-rays will penetrate and is shown of L-shaped cross-section or rabbeted to form a seat as indicated at 21. The front is closed by a plate 22 which may also be of aluminum or Bakelite or other material permeable to the X-rays. This plate is shown flanged at 23 around the frame 20, being flanged over all four sides thereof and suitably fastened by pins or other fastenings indicated at 24. On the inside of the front wall or plate 22 is a cloth or felt cushion lining 25, usually black or dark, the purpose of which will be hereinafter made apparent. 26 designates a back cover which is removable or movable as by hinging the same to the frame 20 through the medium of hinges 27. This back plate or cover may be provided with a cloth or felt cushion lining 28, usually white, both linings forming pads. While the particular construction of this cassette forms no part of the present invention and, therefore, may take any of the forms usual in the art, the same has been described in order to obtain a better understanding of the present invention and the method of marking films and the operation thereof. As shown, suitable means are provided to hold the back or cover 26 closed, such means being illustrated in the form of spring holding means or fasteners in the form of bowed springs 29 pivoted to the cover as at 30 and having the ends thereof adapted to be bent down to enter grooves 31 in the inner faces of the sides of the frame 20 by passing the same through recesses 32 also located in said sides and com-

municating with the grooves but arranged in diagonally opposite positions at opposite sides of the frame and opposite ends of the respective grooves opposing each other at opposite sides of the frame. Of course, any other holding means may be employed. Buttons or spacing pins 33 may, also, be provided at the back so as to engage the upright portion of the support means 19, said buttons or pins projecting from the back plate or cover or provided for any other purpose desired. The felt lining or pad 25 on the inside of the front wall or plate 22 receives an intensifying screen 34 which is usually a fibrous or paper body coated with calcium tungstate or some other fluorescent coating 35 which when impacted with X-rays will give off light. This may be suitably fastened to the lining 25 in a centered position in any suitable way by photographer's paste, glue, or otherwise. A similar screen 36 is likewise attached to the lining or pad 28 carried by the back plate or cover 26 and has a similar coating 37, both coatings or the active sides of the intensifying screens facing inwardly or toward each other. Fig. 1 shows the cassette closed in side elevation and Fig. 2 looking at the back thereof, while Figs. 3 and 4 show the cassette open.

In order to mark the film, the marking medium employed consists in providing the surface 38 of one of the intensifying screens, preferably the one pasted or otherwise fastened to the back or cover 26 as described, with suitable markings shown in the form of horizontal parallel lines 39 designated along one or more margins by suitable calibrations or characters as from A to Z as indicated at 40. The marking medium or sheet consisting of the screen or surface 38 thereof, which is the fluorescent side, is, also, provided with parallel vertical lines 41 designated by numbers from 1 to 39, or otherwise as indicated at 42, these cross-section or coordinate lines intersecting each other at right angles and spaced one-half inch apart or otherwise as desired or preferred according to the size of the X-ray photograph to be produced or the particular object pictured and producing squares of similar size. These markings being on the side of the screen toward the film and permeable to X-rays will not prevent the latter from passing but being opaque to light rays and produced on the surface 38 of the screen with ordinary carbon or india ink by a drawing pen or with other suitable pigment, pencil or marking material in any other suitable way, will pass the X-ray but cut off or block off the light rays from said screen and the film against which the screen is placed or related as more particularly shown in Figs. 5 and 6 of the drawings. In other words, the screens are preferably fastened to the front and back of the cassette at the felt linings and the film is placed in position in the frame so as to be located between the screens when the cassette is closed and fastened by the locking or holding means. A coating, covering, transparent sheet or other means or method may be used to protect and prevent marring or wear on the marking material.

The ordinary double-coated, duplex, or "duplicated" film is designated at 43, the same being normally dark or black and having a base or cellulose portion or sheet in the center with sensitized gelatin coatings 44 and 45 such as heretofore referred to on opposite sides. After the film is placed in position between the intensifying screens and the cassette closed while the film is protected from exposure to ordinary light or active rays in a suitable dark room, the device is

then ready for exposure to the X-rays in the manner shown in Fig. 1 of the drawings. After the X-rays have been on for a few seconds, the same are cut off by extinguishing the tube or lamp 15 and the screens will emanate light rays resulting from the impact and absorption of the X-rays. The X-rays will develop the film a minor degree, say approximately 20 per cent and the screens will develop a major degree, say approximately 80 per cent. The result will be a product or film as shown more particularly in Figs. 10 and 11 of the drawings representing the film developed with the picture or image in the form of a negative produced upon the sensitized coatings on opposite sides of the film to appear as a single image but in which actually one image is superimposed upon the other to produce a highly desirable and more readily discernible photograph. The result is that the bone structure or object such as represented at 16 will be produced upon the film in the form shaded or revised as to the outline shown in Fig. 10 of the drawings in which a midriff or abdominal bone structure is designated by the lines 46. This film is ordinarily a light yellow, ochre, or cream color, but when exposed and developed is black or dark as indicated by the line portion 47 while the image portion 48 on both sides or sensitized coatings of the film are represented as being stippled to indicate the light or shaded portion of the image on the film. The horizontal markings or cross-section lines are designated at 49 as produced by the lines 39 on the screen and 50 designates the image at points of intersection on one side of the film although visible through the same but preferably disposed at the back where the lines intersect the image or representations of the bones or other object X-rayed and which is somewhat lighter than the portions 48. The vertical markings or transparent lines 51 corresponding to the lines 49, as produced by the vertical lines 41 intersect the lines 49 at right angles in the same relation as the cross-section or coordinate lines of the markings on the marking medium or screen and the stippling at the points of intersection of the lines with the image is made lighter to bring out the distinction between the same at points where no markings are produced but without disturbing the continuity of the image, margins or outlines thereof. The action of the screen is such that after the sensitized surfaces thereof have been impacted by the X-rays and the X-ray lamp turned off, these rays impacting with the calcium tungstate or other fluorescent or luminescent coating of the intensifying screens causes the latter to give off light rays, one screen causing the same to be directed toward the film at one side, such as the front, in direct contact therewith while the rays on the other side are directed in the opposite direction toward the film but the markings or lines thereon which are opaque to ordinary light rays but permeable to X-rays results in a photographic image on the film obtained by two stimuli, one being the direct X-rays and the other being the light generated in opposite directions by the intensifying screens. Since the X-rays only produce a minor degree of development on the image of the film and the light rays of the screens produce the major degree thereof, the image will be fully developed on one side where there is no marking medium but on the opposite side where the marking medium or screen has the opaque lines interposed between the same and the film or coating thereof at that side, the light rays from the screen will

be prevented from passing to the film and the result is that the film will be undeveloped or unexposed to the light rays of said screen and the lines will be produced upon the sensitized coating at that side of the film in the form of transparencies which are readily visible upon viewing the film toward a light. Thus, the image will only be fully developed on this side at points not intersected by the markings, but since the film has been partially developed by X-rays on both sides due to the markings being permeable thereto and the image developed by the light rays from the intensifying screen on the side opposite the location of the markings, a complete image will be developed on one side and the light rays from the intensifying screen will develop the image at the portions not intersected by the markings on the side having the markings so that not only the effect of two superimposed images will be produced on the film but the continuity thereof will be unbroken even at the markings, thus rendering a reading more accurate and avoiding the appearance of breaks or fractures in the bone structures such as appears with the old method of marking.

From an observation of the X-ray picture depicted in Fig. 10 of the drawings, it will be seen that misalignments are readily discernible by reason of the parts of the image or bone structure with the calibrated or coordinate markings in this form shown as lines produced from the screen markings or lines as designated in Fig. 3 of the drawings and reference may be had to the calibrations or letters and numbers designating the different lines or columns of rectangular divisions or squares from A to Z and 1 to 30, respectively, or other suitable characters, in describing a part or locating a misalignment and measuring the same without any necessity of marking or obliterating the film. As represented, it will be noted that with a line extending medially and vertically of the spine structure, the ilium or upper part of the dorsal bone at the right-hand side is approximately one-half inch higher than that at the left-hand side. Markings 52 and 53 may be provided upon the film to indicate the right and left-hand sides of the body and these may be produced in any suitable way, by the old method or by the method hereafter described through the medium of markings on the marking sheet so that they will be depicted on the film in the manner illustrated. The transparent markings on the film 43 are indicated at 46F and 42F corresponding to the markings 40 and 42 on the marking sheet or screen 36. It will, also, be noted that other parts, including the hip joints, are correspondingly misaligned, not only as to height, but also shifted to one side or to the right as indicated by the parting at the pelvic bones and thus an anatomist may readily measure and determine the degree of misalignment by viewing the picture and prescribing the necessary treatment for correction. Suitable data, as indicated at 54, may be written with white ink or otherwise marked on the film to identify the person or object photographed, the date of the picture, and any other suitable information.

In Figs. 12, 13 and 14 of the drawings, a modified form of marking is illustrated in which the screen surface 38a is provided with broken or dotted lines or dots in lieu of the solid coordinate lines shown and described in connection with Figs. 3, 9, 10 and 11 of the drawings. Whereas the lines 39 and 41 are drawn on the surface 38 of the screen 36 upon the luminescent coating

such as 37 which may be calcium tungstate as previously described and indicated at 35 and 37 in connection with the screens 34 and 36, they are made directly upon and project from the plane of the coated surface of the screen. However, in this form the dotted or broken lines consist of the horizontal dots 39a and the vertical dots 41a produced at the points of intersection of the lines constituting the markings of the screen and dividing the same into rectangular or square divisions or areas the same as previously described. These lines may also be spaced apart one-half inch or other suitable distance depending upon the type of body or object X-rayed and the size. By having such broken or dotted lines formed simply of dots at the corners of the squares, misalignment can be readily followed from such marking with less obscuring of the image on the film than results from solid lines and without obliterating the image photographed. The dots may be of any form, either solid or as circles and when the film is exposed thereto, the calibrations or characters 40 and 42 of the lines 39a and 41a corresponding to the coordinate lines 39 and 41 in the previously described form will result in the markings or dotted lines 49 and 51 appearing horizontally and vertically of the film 43 and the calibrations or characters will be reproduced on the sensitized surface of the film to also appear as transparencies and exactly correspond to the characters on the screen as indicated at 40F and 42F in Fig. 13 of the drawings. A modification of the marking on the screen which may be either the screen 34 or the screen 36 is shown in Fig. 14 in which, instead of producing the same upon the surface thereof and projecting therefrom as shown in Figs. 3, 9 and 12 of the drawings, may be produced as illustrated in Fig. 14 in which the surface 38 of the fluorescent or luminescent coating 37 on the screen body 36 or the coating 35 on the screen body 34 which are identical therewith, is provided with horizontal lines 39 and vertical lines 41 produced by india ink or other pigment opaque to ordinary light rays, the same as previously described. However, instead of having these markings produced on the flat surface of the screen, the screen may be provided with horizontal recesses 39b or be scored, grooved or scratched into, but not through, the surface 38 as well as the vertical scores or recesses 41b to intersect each other and form grooves in which the ink or pigment is lined or filled, but extending only halfway or partially into the coating 37 as seen in Fig. 14, so as to produce the same below the surface of the coating instead of projecting therefrom and these give greater protection against marring or wear. Of course, it is to be understood that these markings may be produced in any suitable way and that they may be solid lines or dotted lines in accordance with the forms of marking described. It is, also, to be understood that the control of the X-rays, the duration of use thereof and the completion of the picture will not only be hastened by the method herein described but will produce very clear photographs or images on the film together with the markings for determining spaced relationships of bony structures of the body quickly and accurately. The method of developing is the same as any well-known method previously practised.

Thus, instead of employing the old method of applying cross-section markings on a radiograph by interposing an impermeable screen between the source of X-rays and thus the body being X-rayed or photographed and the sensitized film

using screens made of material impervious to X-rays such as grids with lead lines and placed adjacent to or some distance from the sensitized surface of the film with resulting unsatisfactory markings because the lines produced are blurred and the image of the object shown on the radiograph not discernible at all or clearly discernible at line intersections because the continuity of the image is entirely broken by the lines or other markings in view of the fact that no photograph or development of the image appears at such points, the present invention overcomes such objections and results in a much clearer image, the continuity of the body and margins of which is entirely unbroken. The invention does not require the interposition of an impermeable marking between the source of the X-rays and the sensitized film and, therefore, the lines produced, while easily discernible, do not obliterate or cause breaks in the continuity of the body or margins but render the same continuous and the details of the image of any object are sharply defined due to the marker being in direct intimate contact with the sensitized surface of the film. While it is not new to use a film or plate coated on both sides with a layer of emulsion containing certain silver compounds or other sensitized coating and subjecting the same to the direct emanations of X-rays or using intensifying screens which act upon the sensitized surfaces of the film after the impact of the X-rays thereon, it is new to interpose a marking medium between a sensitized screen and a surface of a film so that the light rays from such screen thrown against the marking sheet with the markings thereon opaque, impervious or impermeable to the light rays from the screen, though permeable to the X-rays, will produce the markings on the film which appear substantially as transparencies on one side. The result is that the image developed by the X-ray on that side is partially visible in addition to the visibility of the image fully developed on the opposite side of the film and uninterrupted by any markings as said images are lightly or partially developed or produced throughout the entire areas on both sides of the film by the X-rays. On the other hand, the light rays from the intensifying screen at one side opposite the markings or where no marking device is located, will affect the entire film and produce a complete image, including at as well as between the lines, whereas the light rays from the intensifying screen at the opposite side where the markings are located will affect only those areas between the lines and not at the lines where the opaque markings prevent the passage of the light rays from the latter screen to the film.

In other words, the markings or lines on the film can be seen when viewing the film from either or both sides, appearing substantially as transparencies, but are actually produced on one side only, i. e., that side where the markings are located closely adjacent or in intimate contact with the film. On this side, the image will only be developed by the X-rays where the markings or lines are located and not by the light rays from the screen at said side as the opaque markings or lines will cut or block off the ordinary light rays from the screen and prevent action thereby on the film, but all areas between the lines on both sides of the film will be affected by the X-rays and light rays from the screens on both sides, thus resulting in the image being unbroken and visible at the transparent lines on the film as well as at other points, instead of the

image being invisible or blotted out entirely at the lines to produce a defective broken picture as with old methods of marking.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the scope of the appended claims.

Having thus described our invention, what we claim as new and desire to secure by Letters Patent is:

1. A method of marking transparent coordinate lines on double-coated films consisting in interposing the image area of the film between two intensifying screens adapted to give off light when impacted by X-rays through a body to be pictured and marking on the surface of only one screen disposed toward the film, intersecting vertical and horizontal lines of a medium permeable to X-rays but impermeable to light rays produced by the screen after being impacted by the X-rays while leaving the light rays against the opposite side of the film from the opposite screen unobstructed.

2. A method of marking double-coated films consisting in interposing the film as held in a cassette between two intensifying screens adapted to give off light when impacted by X-rays and marking on the surface of one screen disposed toward the film over the image area thereof, intersecting vertical and horizontal markings produced by material pervious to X-rays but impervious to light rays from the screen while leaving the opposite side of the film unobstructed to light rays from the other screen, whereby the image of the object pictured will be produced upon both sides of the film by the X-rays, completely on one side by the light rays from the screen at that side and on the other side by the light rays from the other screen, except at the points of locations of the markings on said other screen so as to produce the markings on the film at said side in the form of transparencies.

3. An X-ray film marker consisting of a luminescent medium adapted to be placed against a film in X-raying an object, having intersecting vertical and horizontal lines thereon opaque to light rays over the object area.

4. An X-ray film marker consisting of a luminescent sheet adapted to be placed on one side of a "dupletized" film, having intersecting vertical and horizontal lines thereon opaque to light rays and permeable to X-rays.

5. An X-ray film marker consisting of a luminescent screen held in a cassette in the X-raying of an object, having markings thereon to extend over the image area, opaque to light rays and permeable to X-rays.

6. An X-ray intensifying screen having intersecting vertical and horizontal lines thereon permeable to X-rays and impermeable to ordinary light rays.

7. An X-ray intensifying screen having intersecting vertical and horizontal solid lines thereon permeable to X-rays and impermeable to ordinary light rays.

8. An X-ray intensifying screen having inter-

secting vertical and horizontal broken lines thereon permeable to X-rays and impermeable to ordinary light rays.

9. An intensifying and film marking screen having markings thereon opaque to ordinary light rays, said markings being embedded in the surface of the screen.

10. A method of making a film marker consisting in producing coordinate depressed lines on an X-ray intensifying screen permeable to X-rays and opaque to light rays from the screen.

11. A method of making a film marker consisting in producing coordinate depressions in the coated side of an intensifier screen as used in photographing an object on a "dupletized" film and filling said depressions with material transparent to X-rays and opaque to light rays from the screen.

12. A method of marking the object or image area of a film with coordinate transparent lines consisting in exposing one side only of the film while disposed against one side of an X-ray screen having coordinate lines thereon opaque to ordinary light rays but transparent to X-rays to extend over said area.

13. A method of marking the object area of films as used in making roentgenograms to indicate at a glance alignment or misalignment and spaced relationship to each other of bone structure or parts of objects X-rayed, consisting of exposing one side of the film to an intensifying screen having intersecting parallel lines thereon normal to each other over the image area of the film opaque to light rays from the screen and transparent to X-rays whereby said lines will appear on the film as transparencies while maintaining the image in unbroken form.

14. A method of marking double-coated films with coordinate transparent markings over substantially the entire area thereof, consisting in interposing the film as held in a cassette between two intensifying screens adapted to give off light when impacted by X-rays through a body to be pictured, and exposing the entire image area of the film to coordinate markings on the surface of one screen disposed toward the film and composed of a medium permeable to X-rays and impermeable to light rays.

15. A method of marking X-ray films over substantially the entire image area thereof with coordinate transparent markings, consisting in subjecting the film as held in a cassette in X-raying an object, to the action of X-rays while in contact with an intensifying screen having a surface adapted to give off light rays after exposure to X-rays and having coordinate markings thereon extending over substantially the entire areas of the film and screen and being permeable to X-rays and impermeable to light rays from the screen, cutting off the X-rays and then exposing the film to the action of the light rays of the screen only, whereby the film will be shielded at the point of the markings from the light rays of the screen to produce said coordinate transparent markings over a complete image on at least one side of the film without interrupting the continuity of the image or resulting in breaks or fractures therein.
